BIRD CAGE ORNAMENT

Mae Frances Tatlock, Los Angeles County, Calif.
(15311 Roscoe Blvd., Van Nuys, Calif. 91401)

Filed Apr. 6, 1967, Ser. No. 8,202

Term of patent 14 years

(Cl. D29—1)

FIG. 1 is a front view of a bird cage ornament, embodying my new design; and

FIG. 2 is a top plan view thereof.

This is a continuation-in-part of design application Ser. No. D. 2,797, filed June 20, 1966, and now abandoned.

I claim:

The ornamental design for a bird cage ornament, substantially as shown.
